CLAIM

The ornamental design for an LED street light, as shown and described.

DESCRIPTION

FIG. 1 is an upper perspective view of an LED street light showing my new design.

FIG. 2 is a lower perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The elements presented in broken lines represent unclaimed portions of the LED street light and unclaimed labeling and form no part of the claimed design.
